LID SUPPORT

George H. Johnson, Rockford, Ill., assignor to The Atwood Vacuum Machine Company, Rockford, Ill., a copartnership composed of Seth B. Atwood and James T. Atwood

Application April 5, 1937, Serial No. 135,060

7 Claims. (Cl. 217—60)

This invention relates to lid supports, or more generally stated, supports for liftable hinged closures, and is herein specially concerned with a support suitable for use on the lids for rear trunks or luggage compartments on automobiles.

The lid supports now commonly used comprise two pivotally connected arms or links attached to the body and lid and arranged to unfold out of the luggage compartment in the opening of the lid. An objection to that type of support has been that there was danger of getting something pinched between the arms in folding, or of the arms poking into something in the luggage compartment and causing damage thereto in the closing of the lid. It is therefore the principal object of my invention to provide a support made up of two telescoping members slideable relative to one another in the opening and closing of the lid, whereby to avoid the dangers of damage or injury attributable to the "scissors" action of the other type of supports and the objections due to the "elbow" room required with that type.

Another object consists in the provision of simple but positively acting means for releasably locking the telescoping members in extended relation so that a predetermined endwise movement of the one member relative to the other produced by movement of the lid is sufficient to unlock the members for return movement to normal or retracted telescoped relation.

Other objects and advantages of the invention will soon appear in the following description, wherein reference is made to the accompanying drawing, in which—

Fig. 1 is a section through a portion of the luggage compartment on the rear of an automobile showing a support made in accordance with my invention applied to the lid or door thereof, the mode of operation of the support being indicated by the dotted line showing of the lid in raised position;

Fig. 2 is a rear view of the support with the parts shown in the dotted line position of Fig. 1;

Fig. 3 is a side view on a larger scale of the middle portion of the support in the position of Fig. 2;

Fig. 4 is a cross-section on the line 4—4 of Fig. 3;

Figs. 5 to 9 are sections in the plane of the line a—a of Fig. 2 showing the telescoping support members in the different positions throughout a cycle starting with the raising of the lid and ending with the lowering thereof, Fig. 5 of this series showing the members in the position of

Fig. 1, and Fig. 7 of this series showing the members in the position of Fig. 2;

Fig. 10 is a side view of a one-piece cam block which may be used in place of the two separate blocks shown in Figs. 5 to 9, and

Figs. 11 and 12 are two views of still another modification in the construction wherein the cams are formed by struck out portions of the wall of one of the telescoping members, Fig. 12 being a section on the line 12—12 of Fig. 11.

Similar reference numerals are applied to corresponding parts throughout the views.

Referring first to Figs. 1 and 2, the numeral 13 designates the rear trunk or luggage compartment on an automobile, and 14 its door or lid hinged at 15 to permit raising and lowering the same, as indicated in the full and dotted line positions. 16 and 17 are two supporting arms or links pivotally attached at 18 and 19, respectively, to the side wall of the trunk 13 and edge portion of the lid 14, as shown. The arms 16 and 17, in accordance with my invention, are in slideable telescoping relation and in the closed position of the lid are telescoped on one another substantially their full length, as shown in full lines in Fig. 1, taking up a minimum amount of room inside the trunk, much less room than was required with the other style of folding supports. The arm 17 slides on the arm 16 when the lid 14 is raised, and the arms are arranged to be locked releasably in the extended relationship by the novel means hereinafter described, whereby to support the lid in raised position, as indicated in dotted lines in Fig. 1 and as illustrated in Fig.

2. The fact that the arms slide on one another in a telescoping fashion eliminates any danger of something getting caught between the parts in the closing of the lid. In other words, this type of support, besides requiring less "elbow" room in the trunk in the closing of the lid, and hence avoiding likelihood of the support doing damage to something placed in the trunk, presents no danger of damage or injury like the other style of supports where the arms folded in "scissors" fashion and might therefore pinch something that happened to get caught between the arms in the closing of the lid.

The arm 16, as clearly appears in Fig. 4, is formed from sheet metal to channel-shaped cross-section, and the same is true of the arm 17, but the arm 16 simply has its longitudinal flanges 20 bent at right angles thereto and slideable between the flanges 21 of the arm 17, the arms being in opposed relation, as shown, so that the bottoms or webs of the channels are

in spaced relation. The marginal edge portions of the flanges 21 are bent inwardly behind the arm 16 to hold the arms in telescoping relation. A pawl 23 is pivotally mounted on a stud 24 and has two teeth 25 and 26 substantially at right angles to one another. A pin 27 carried on the tooth 26 extends through a slot 28 provided in the arm 17 struck on an arc with the stud 24 as a center. To the outer end of this pin is attached a coiled tension spring 29 which is stretched to a predetermined extent and anchored to the arm 17 in any suitable manner as on a pin 30. This spring normally holds the pawl 23 in a dead-center neutral position, as shown in Figs. 5 and 8, in which views it will be noticed that the pins 27 and 30 and stud 24 are in line. Under these conditions it will also be noted that the pin 27 is in an intermediate position in the slot 28. Now, the arm 16 has two cam blocks 31 and 32 suitably secured thereto in abutment with one of the flanges 20 and in a predetermined longitudinally spaced relation. The block 31 has one corner thereof notched to provide a ledge or shoulder 33 thereon facing the block 32 arranged to be engaged by the tooth 25 of the pawl 23, as in Fig. 7, whereby to lock the arms releasably in extended relationship supporting the lid 14. The other block 32 has one corner thereof formed with an acute angled projection 34 extending toward the block 31 and arranged to engage the tooth 26 of the pawl 23, as in Fig. 6, to limit outward movement of the arm 17 relative to the arm 16 when the lid is being raised from closed position preparatory to its being releasably locked in open position. This same projection 34 will strike the hub 35 of the pawl 23, as in Fig. 8, to limit outward movement of the arm 17 relative to the arm 16 when the lid is raised slightly from the dotted line position of Fig. 1 to release the pawl 23 from the cam 31 preparatory to the lid being lowered to closed position.

In operation, when the lid is closed, the pawl 23, being on the lower end of the arm 17, is of course in remote relation to the cam blocks 31 and 32 which are on the upper end of the arm 16, as must be evident from an inspection of Fig. 1. In Fig. 5, the pawl is shown in full lines in its normal dead-center or neutral position, just prior to its encountering the block 31 as the lid 14 is being raised. The tooth 25 strikes the block 31 as the pawl moves past it, and the pawl is turned slightly in a clockwise direction against the action of the spring 29, as indicated by the dotted line position of the pawl in Fig. 5. This slight clockwise movement throws the tooth 26 far enough to the right where it is bound to strike the projection 34 when the tooth 25 rides off the surface 36 on the block 31, as illustrated in Fig. 6. That positively limits further upward movement 60 of the lid 14, and the operator then lowers the lid, whereupon the spring 29 which tends to return the pawl 23 to dead-center position again, turns the pawl in a counterclockwise direction the moment the tooth 26 rides off the projection 34 in the lowering of the lid, and the tooth 25 is thereby thrown into contact with the surface 37 on the block 31. This stops the turning of the pawl under spring action, and the tooth 25 rides along the surface 37 and comes to rest on the ledge 33, thus preventing further downward movement of the lid 14 and locking it releasably in raised position, substantially as shown in dotted lines in Fig. 1. The lid is securely, though releasably, locked in raised position, because it requires a definite predetermined amount of up-

ward movement of the lid 14 to release the pawl 23 and permit the lid to be lowered and closed. Obviously, if the lid is raised slightly, the tooth 25 will simply ride up on the surface 37 and return again to the ledge 33 so that the lid is not apt to be unlocked accidentally either under pressure of the wind against it or by the operator happening to brush against the lid in putting things into or removing things from the trunk 13. While a relatively short length of surface 37 is shown on the block 31, it is obvious that a longer surface could be provided if desired, and thus permit of proportionately increased free movement of the lid without releasing the pawl when the lid is locked in its raised position. When the lid is to be lowered and closed again, the operator simply grasps the lid and raises it so that the hub 35 of the pawl 23 strikes the projection 34 on the block 32, as shown in Fig. 8. In this movement, the tooth 25 leaves the surface 37 and the pawl 23 is moved in a counter-clockwise direction under spring action to dead-center position. The engagement of the pawl with the projection 34 positively limits the upward movement of the lid so that the operator knows definitely that the lid is unlocked and may be closed. As the lid is lowered toward closed position, the tooth 25 of the pawl 23 in riding over the block 31 is turned in a counterclockwise direction through approximately 90° against the action of the spring 29, as shown in Fig. 9, and, of course, as soon as the tooth 25 rides off the block 31, the spring 29 immediately returns the pawl 23 to dead-center position, as in Fig. 5. The pawl is therefore in position for the commencement of the next cycle of operation. The spring 29 keeps the only freely movable part of the support under spring tension at all times, so that there is nothing apt to rattle when the lid is closed and the car is in motion. There is furthermore very little strain imposed upon the spring 29 at any time, so that it is not at all apt to break and throw the support out of commission. If the spring does break, it is apparent at a glance because it is exposed on the outside of the support, and in that case a new spring can be substituted very easily without having to take the support apart.

In Fig. 10 I have shown a modified or alternative construction in which a single block 38 takes the place of the blocks 31 and 32, the ledge 33' and projection 34' provided on this block corresponding to the ledge 33 and projection 34 on the blocks 31 and 32, respectively. By having these portions on one block, the accurate spacing thereof is more definitely insured than where two blocks are fastened in place separately, and, of course, that is very important. The block 38 is further provided with surfaces 36' and 37' corresponding to the surfaces 36 and 37 on the block 31. The operation secured with this construction would obviously be the same as with the other construction.

If desired, I may eliminate the blocks 31 and 32 entirely and simply strike out a lug 31a from the web of the channel member 16' in place of the block 31 and strike out another lug in place of the block 32. The lug 31a, it will be noticed, is profiled to provide the surfaces 36'' and 37'' corresponding to the surfaces 36 and 37 on the block 31, in addition to the ledge 33'' corresponding to the ledge 33 on the block 31. Obviously the other lug taking the place of the block 32 would be profiled similarly as the block 32 with a projection like the projection 34, and, of course, the other lug would be provided in the same

spaced relation to the lug 31a as the block 32 is spaced from the block 31.

It is believed the foregoing description conveys a good understanding of the objects and 5 advantages of my invention. The appended claims are drawn with a view to covering all legitimate modifications and adaptations.

I claim:

1. A device of the character described comprising an arm pivotally attached to a lid or other hinged member, another arm in telescoping relation with the first arm and pivotally attached to a receptacle or other support on which the lid is hinged, a pawl pivotally mounted on 10 one of said arms, abutments on the other arm for engagement with the pawl to limit endwise movement of one arm relative to the other toward coextensive telescoping relation and also 15 releasably lock said arms in coextensive telescoping relation whereby to support the lid in open position, said abutments being arranged to engage the pawl and cause it to turn in both directions about its pivot to and from locking position in reciprocatory movement of the arms relative to one another, a projection on the pawl extending through a slot provided in the pawl-carrying arm struck on an arm with the pawl pivot as a center, and spring means cooperating 20 with the projection on the outside of the pawl-carrying arm normally tending to move the pawl to an intermediate dead-center position.

2. A device of the character described comprising an arm pivotally attached to a lid or other hinged member, another arm in telescoping relation with the first arm and pivotally attached to a receptacle or other support on which the lid is hinged, a pawl pivotally mounted on 25 one of said arms having two teeth in approximately right-angle relationship, spaced projections on the other arm arranged in different positions of the pawl-carrying arm relative thereto to be engaged by the pawl to limit endwise movement of one arm relative to the other toward coextensive telescoping relation and also 30 releasably lock said arms in coextensive telescoping relation whereby to support the lid in open position, said projections being arranged to engage the teeth and cause the pawl to turn in both directions about its pivot to and from locking 35 position in reciprocatory movement of the arms relative to one another, and means normally tending to return the pawl to an intermediate dead-center position.

3. A device of the character described comprising an arm pivotally attached to a lid or other hinged member, another arm in telescoping relation with the first arm and pivotally attached to a receptacle or other support on which the lid is hinged, a pawl pivotally mounted on 40 one of said arms having two teeth in approximately right-angle relationship, spaced projections on the other arm arranged in different positions of the pawl-carrying arm relative thereto to be engaged by the pawl to limit endwise movement of one arm relative to the other toward coextensive telescoping relation and also 45 releasably lock said arms in coextensive telescoping relation whereby to support the lid in open position, said projections being arranged to engage said teeth and cause the pawl to turn in both directions about its pivot to and from locking 50 position in reciprocatory movement of the arms relative to one another, a projection on one of said teeth extending through a slot provided in the pawl-carrying arm struck on an

arc with the pawl pivot as a center, and spring means on the outside of said arm cooperating with the projection and tending normally to hold the pawl in an intermediate dead-center position.

4. A device of the character described comprising arms pivotally attached to a lid or other hinged member and to a receptacle or other support on which the lid is hinged, said arms being of channel-shaped cross-section, one of 10 said arms having its flanges extending toward the web of the other arm and slidably between the flanges thereof, means for retaining said arms in telescoping relation, a pawl pivotally mounted on the web of one of said arms, projections on the web of the other arm for detachable engagement by the pawl upon endwise movement of one arm relative to the other to limit endwise movement of one arm relative to the other toward coextensive telescoping relation and also 15 releasably lock said arms in coextensive telescoping relation whereby to support the lid in open position, said projections being arranged to engage the pawl and cause it to turn in both directions about its pivot to and from locking 20 position in reciprocatory movement of the arms relative to one another, said pawl having a projection extending through a slot in the web of the pawl-carrying arm struck on an arc with the pawl pivot as a center, and spring means on 25 the outside of said web cooperating with said projection and tending normally to hold the pawl in a dead-center position.

5. In a device of the class described, a first channel arm, a second channel arm slidably endwise relative thereto in telescoping relation so that the web portions of the arms are in spaced 30 parallel relation, one of said arms having a slideable lug member on the inner side of the web portion thereof and the other having a cooperating track on the inner side of the web portion thereof, said track having an extension limit stop portion arranged to be engaged by said lug when the arms are slid outwardly relative to each other, a contraction limit stop portion engaged by said lug when the arms are slid inwardly relative to each other, spring means on 35 the outer side of the web portion of the first named arm for actuating said lug member to predetermined positions relative to said stop portions in different positions of said arms, said arm having a slot in the web portion thereof, and means working in said slot interconnecting said spring means and said slideable lug member.

6. A device of the character described comprising an arm pivotally attached to a lid or other hinged member, another arm in telescoping relation with the first arm and pivotally attached to a receptacle or other support on which the lid is hinged, a pawl pivotally mounted on 40 one of said arms having two teeth in approximately right-angle relationship, two spaced projections on the other arm, one of which is arranged to engage one tooth of the pawl to bring the other tooth of the pawl into position to engage the other projection, whereby to limit endwise movement of one arm relative to the other toward coextensive telescoping relation, the first named projection being thereafter arranged to engage the first named tooth to limit return 45 movement of the first arm relative to the other arm so as to releasably lock the arms in coextensive telescoping relation and support the lid in open position, a projection on said pawl extending through a slot provided in the pawl carry- 50

ing arm struck on an arc with the pawl pivot as a center, and spring means on the outside of said arm cooperating with the projection and tending normally to hold the pawl in a predetermined position with relation to said projections.

7. A device of the character described comprising an arm pivotally attached to a lid or other hinged member, another arm in telescoping relation with the first arm and pivotally attached to a receptacle or other support on which the lid is hinged, a pawl pivotally mounted on one of said arms having two teeth in approximately right-angle relationship, two spaced projections on the other arm, one of which is arranged to engage one tooth of the pawl to bring the other tooth of the pawl into position to engage the other projection, whereby to limit end-

wise movement of one arm relative to the other toward coextensive telescoping relation, the first named projection being thereafter arranged to engage the first named tooth to limit return movement of the first arm relative to the other arm so as to releasably lock the arms in coextensive telescoping relation and support the lid in open position, and spring means normally tending to return the pawl to a predetermined position with relation to said projections, the pawl being so constructed and the projections being so spaced in relation to the teeth of the pawl that the first named tooth catches on the first named projection on alternate relative reciprocations of said arms, but said tooth rides freely over said projection on intermediate relative reciprocations.

GEORGE H. JOHNSON.

CERTIFICATE OF CORRECTION.

Patent No. 2,229,506.

January 21, 1941.

GEORGE H. JOHNSON.

It is hereby certified that error appears in the printed specification of the above numbered patent requiring correction as follows: Page 3, first column, line 27, claim 1, for the word "arm" second occurrence, read --arc--; and that the said Letters Patent should be read with this correction therein that the same may conform to the record of the case in the Patent Office.

Signed and sealed this 25th day of February, A. D. 1941.

Henry Van Arsdale,
Acting Commissioner of Patents.
